ELECTRICAL SOUND REPRODUCING APPARATUS

Harry C. Warner, San Francisco, Calif.

Application August 14, 1944, Serial No. 549,379

8 Claims. (Cl. 179—100.41)

1

My present invention relates to electrical sound reproducing apparatus, and more particularly to a device for providing a modulated input signal current for a vacuum tube amplifying system.

An object of the invention is to provide a new and novel form of current modulating device which is particularly adapted to operate in conjunction with a sound responsive device, such as a phonograph pick-up or microphone, to provide an input signal current for a vacuum tube amplifier circuit.

Another object of the invention is to provide a current modulating device of the resistance type in which the resistance of a liquid conducting medium may be varied in a new and novel manner to provide a signal current for the input of a vacuum tube amplifying system.

A further object of the invention is to provide a phonograph pick-up device of novel construction for use with a vacuum tube amplifying system of the type employed to reproduce the recording upon a sound record.

Other objects and advantages of the invention will be in part evident to those skilled in the art, and in part pointed out hereinafter in the following description taken in connection with the accompanying drawing, wherein there is shown by way of illustration and not of limitation, preferred embodiments of the invention.

In the drawing:

Figure 1 is a substantially normal-size view of the invention as embodied in a pick-up for the tone arm of a phonograph.

Figure 2 is an enlarged sectional view with parts broken away and showing details of construction of a preferred embodiment of a feature of the invention.

Figure 3 is a transverse sectional view taken along line III—III of Figure 2.

Figure 4 is a diagrammatic wiring diagram showing a system of connections by which my device may be associated with the input of a vacuum tube amplifying circuit, and

Figures 5 and 6 are diagrammatic views showing other adaptations of the invention.

In Figure 1 of the drawing, for the purpose of illustration, I have shown my invention as embodied in a pick-up device, such as may be used to electrically reproduce the recorded program upon a sound record. In this showing the numeral 10 designates a supporting housing of insulating material, such as is now generally used as a mounting for a piezo-electric crystal of a phonograph pick-up device. This housing 10 is constructed in two substantially symmetrical

2

parts between which terminals 11 and 12 extend from one end for connection with a vacuum tube amplifier circuit. At their other end the halves of the housing 10 are provided with diagonally disposed and registering half-round grooves 13 that will provide a cylindrical seat for two relatively soft rubber collars 14 and 15 within which a record needle supporting member 16 is pivotally mounted. Carried by the member 16 there is a suitable thumbscrew 17 by means of which a needle 18 may be secured within the support 16. Extending inwardly, and also carried by the support 16, there is an operating arm 19 that is adapted to control a variable resistance device 20 which embodies what are now considered to be the novel aspects of my present invention. As here shown, the variable resistance device 20 is in the form of a small capsule which is positioned within a recess 21 formed in one side of the housing 10 so that its axis will be approximately in line with a projection of the axis of the record engaging needle 18. As will hereinafter appear, the device 20 is believed to operate on the principle of a variable resistance and it is here shown as being connected at its ends through conductors 22 and 23 to the terminals 11 and 12 which in turn are adapted to connect with the input terminals of a vacuum tube amplifier circuit.

Reference is now made to Figures 2 and 3 of the drawing for a more detailed description of the invention as embodied in a device suitable for use as above indicated. In these figures the device 20 illustrated in Figure 1 is shown on a greatly enlarged scale. As at present constructed, the unit or capsule has a diameter of approximately seven thirty-seconds of an inch and an overall length of one-half inch, and the amount of liquid required as a variable resistance medium, as will hereinafter appear, amounts to approximately two full drops. In its preferred form the device 20 comprises a length of relatively soft rubber tubing 24 that is adapted to be closed at its ends by means of electrodes 25 and 26 that project into the ends thereof so as to form an air-tight liquid containing chamber 27 therebetween which is adapted to be filled with a liquid resistance medium. As here shown, the electrodes 25 and 26 are each provided with an annular recess 28 into which the ends of the tubing 24 are clamped by means of suitable binding rings 29. Extending between the electrodes 25 and 26 there is a spacing member 30 of insulating material which is seated at its ends within the electrodes 25 and 26 in such a manner that they will be held in properly spaced relation with respect to each

other. This spacing member 30 has an annular collar or enlargement 31 intermediate its ends which is chamfered so as to provide for a substantially knife edge engagement thereof with the inside wall of the tubing 24, and at one point around its circumference, as is more clearly shown in Figure 3 of the drawing, this annular collar or enlargement 31 is provided with a notch or cut-away portion 32 that serves to provide a constricted conductance path in the liquid resistance medium contained within the chamber 27. As is more clearly shown in this latter figure of the drawing, the rubber tubing 24 is adapted to be engaged on its outer surface, at a point immediately adjacent the notch or cut-away portion 32, by the operating member 19 previously referred to as actuated in accordance with the movements of the record engaging needle 18 when the latter is operating upon a sound recording.

In Figure 4 of the drawing I have shown a diagrammatic circuit by means of which my invention may be associated with a vacuum tube amplifier circuit. At this point it should be stated that while it is believed that the operation of my improved device is based upon the principle of a variable resistance as a modulating means, it is to be understood that this action may be accounted for by some other theory. The nature of the liquid resistance medium does not appear to be of major importance, but it has been found that grain alcohol or, in fact, ordinary whiskey, may be used as a resistance medium between the electrodes 25 and 26. The fact that an alcohol, as distinguished from an acid electrolyte, has been found to be particularly effective in this instance, may be due to its inactivity with respect to the rubber tubing. There is also the known fact that the alcohols have a high inductive capacitance value and it is, therefore, possible that the use of such a liquid resistance medium may in some way involve a capacitive change in the circuit between the electrodes 25 and 26. In any event, it has been demonstrated by actual use that a device constructed as above described is capable of providing for the reproduction of recorded music in a much smoother and more satisfactory manner than is possible with the best piezo-electric crystals now on the market for this purpose. Among other advantages, it has been found possible, by changing the resilience or thickness of the tubing 24, to provide for almost any desired frequency response. For example, a thin walled tubing has been found to be very responsive in the higher frequency range, while in the lower frequency range the response is more pronounced as the thickness of the tubing 24 is increased. Another point is that by changing the nature of the liquid and/or the length of the current path therethrough, it will be possible to match the input impedance of any amplifier circuit with which the device may be used. And finally, it has also been discovered that the operation of the device is not affected by changes in temperature or humidity, which is a characteristic not possessed by the so-called piezo-electric crystal microphone and pick-up devices.

In operation, when the device 20 is associated with a vacuum tube amplifier circuit, as diagrammatically shown in Figure 4 of the drawing, one of its electrodes, as for example, the electrode 25, will be connected through a conductor 33, a coupling resistor 34 and a conductor 35 to the positive side of the output or plate circuit of a vacuum tube 36, which tube is here shown as having a control grid 37, a filament 38 and a plate

39. This electrode 25 is also shown as connected through a capacitance 40 to the grid 37 of the vacuum tube 36. At the other side of the device 20 the electrode 26 is connected through a conductor 41 to the grounded side of the filament 38 and through a grid leak resistance 42 to the grid 37 of the vacuum tube 36. A plate coupling resistance 43 is also here shown as connected across the plate or output circuit of the vacuum tube 36. This output circuit also has a blocking capacitance 44 in one side thereof. When the device 20 is connected in this manner, it is believed that a current flow will be established through the conductor 35, the coupling resistance 34 and the conductor 33 to the electrode 25, and from there through the variable resistance medium to the electrode 26 and via the conductor 41 to ground at the point of connection with the filament 38 of the vacuum tube 36. Now, with this current flowing through the variable resistance medium of the device 20, it will be seen that when the recording needle 18 is stationary, no change will occur in the nature of the conductance path between the electrodes 25 and 26 and, therefore, a substantially uniform flow of current will prevail. However, when the nature of the conductance path formed by the resistance liquid medium in the constricted zone of the chamber 27 is varied, as by movements of the record engaging needle 18, it is believed that these changes will produce a modulation of this current which will then be transmitted through the condenser 40 and the grid leak resistance 42 to the grid 37 of the vacuum tube 36, and in this way the vacuum tube 36 will operate to produce an amplified signal current that may be used to operate a loud speaker or other similar device. It is also conceivable that the circuit through the variable resistance liquid medium of the device 20 may also be subjected to a high frequency carrier current originating in the plate circuit of the vacuum tube 36 upon which the modulated signal current may be superimposed.

While I have illustrated and described my invention as embodied in a device for use in connection with the reproduction of phonograph recordings, it will be readily understood that the device 20 may be found useful in other fields. For example, as shown in Figure 5 of the drawing, it may be used in connection with a sound wave responsive microphone by operating the device 20 in association with a sound wave intercepting diaphragm 45 or, as shown in Figure 6 of the drawing, wherein the device is illustrated as associated with a mechanically operated detector device 46 that may be placed against any vibrating surface for the purpose of reproducing electrical impulses corresponding to the movements of a vibrating member.

While I have, for the sake of clearness and in order to disclose the invention so that the same can be readily understood, described and illustrated specific devices and arrangements, I desire to have it understood that the invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is:

1. In a phonograph pick-up of the character described, the combination of a supporting hous-

ing adapted to be carried by the tone arm of a phonograph, a stylus pivotally mounted upon and extending from said housing adapted to engage a sound record, a deformable liquid containing receptacle having spaced electrodes mounted therein and adapted to be connected in the grid circuit of a vacuum tube with the plate to ground potential of said vacuum tube impressed therebetween, a current conducting liquid within said receptacle forming a variable conductance path between said electrodes, and means operated by movements of said stylus adapted to deform said receptacle and thereby change the conductance of said liquid in accordance with the recording upon a sound record.

2. In a phonograph pick-up of the character described, the combination of an insulated supporting housing adapted to be carried by the tone arm of a phonograph, a stylus pivotally mounted upon and extending from said housing adapted to engage a sound record, a tubular rubber receptacle having spaced electrodes closing the ends thereof and adapted to be connected in the input circuit of a vacuum tube with the plate to ground potential of said vacuum tube impressed therebetween, a liquid medium within said receptacle forming a variable conductance path between said electrodes, and means operated by movements of said stylus adapted to deform said tubular receptacle between said electrodes to thereby vary the cross-section and conductance of said liquid between said electrodes in accordance with the recording upon a sound record.

3. In a control device for vacuum tube circuits, the combination of a tubular non-metallic member having current conducting electrodes forming closures at the ends thereof, a current conducting liquid forming a conductance path within said tubular member between said electrodes, means forming a constricted cross-section of said liquid at a point between said electrodes, and a sound wave responsive means adapted to deform said tubular non-metallic member at the point of said constriction to thereby change the overall conductance of said liquid between said electrodes in accordance with sound wave impulses to which said sound wave responsive means may be exposed.

4. In a sound wave control device for vacuum tube circuits, the combination of a grid controlled vacuum tube, a receptacle having opposed and insulated electrodes mounted therein and adapted to be connected through a capacitance in the grid circuit of said vacuum tube, connections whereby the plate potential of said vacuum tube is impressed across the space between said electrodes, a liquid current conducting medium disposed between said electrodes, means located between said electrodes forming a restricted current path in said liquid, and mechanical means responsive to sound wave impulses adapted to vary the cross-section of the restricted current path in said liquid in accordance with the nature of sound wave impulses to which said mechanical means is exposed.

5. In a sound reproducing vacuum tube circuit,

the combination of an input tube having filament, grid and plate connections, a variable resistance medium comprising spaced electrodes with a column of conducting liquid therebetween, circuit connections between one of said electrodes and the plate and through a capacitance to the grid of said vacuum tube, a circuit connection between the other of said electrodes and the filament grounding circuit of said tube, whereby the plate potential of said tube will be impressed upon said liquid through said electrodes, and mechanical means responsive to sound wave impulses adapted to vary the cross-section of said column of conducting liquid between said electrodes, whereby a modulated current corresponding to the response of said sound wave responsive means will be impressed upon the grid of said input tube.

6. In a variable resistance unit for a current modulating device, the combination of a pair of spaced electrodes, a tubular rubber sleeve secured at its ends around each of said electrodes and forming a liquid containing chamber therebetween, means between said electrodes operating to divide said chamber into two parts with a restricted communicating passageway therebetween, a current conducting liquid disposed within said chamber forming a variable resistance between said electrodes, and means including a sound wave responsive device adapted to distort the wall of said tubular sleeve adjacent said restricted passageway, whereby the overall resistance of said liquid conducting medium will be changed in accordance with the operation of said means.

7. In a control device for vacuum tube circuits, the combination of a capsule-like unit comprising an elongated yielding body portion of insulating material having current conducting electrodes sealed in and closing the ends thereof to provide a fluid containing cavity, a fluid medium disposed within said capsule and forming a current conducting path between said electrodes, and means associated with the yielding body portion of said capsule adapted to exert a deforming pressure thereupon, whereby the conductance of the current path through said fluid medium between the electrodes at the ends of said capsule will be varied in accordance with the operations of said means.

8. In a control device for vacuum tube circuits, the combination of a capsule-like unit having a yielding body portion of insulating material, current conducting electrodes sealed in the wall of said capsule and forming therewith a closed fluid containing cavity, a fluid medium disposed within said capsule between said electrodes and forming a current conducting path therebetween, and means associated with the yielding body portion of said capsule adapted to exert a deforming pressure thereupon, whereby the conductance of the current path through said fluid between said electrodes will be varied in accordance with the operations of said means.

HARRY C. WARNER.
